CLAIM

The ornamental design for a chain link module for a conveyor belt, as shown and described.

DESCRIPTION

FIG. 1 is a top view of a chain link module for a conveyor belt embodying the new design.

FIG. 2 is a bottom view thereof;

FIG. 3 is a right side view thereof;

FIG. 4 is a left side view thereof;

FIG. 5 is a top view of a chain link module for a conveyor belt similar to the embodiment of FIG. 1, but in a broader version.

FIG. 6 is a bottom view of the chain link module in FIG. 5; FIG. 7 is a right side view of the chain link module in FIG. 5,

FIG. 8 is a left side view of the chain link module in FIG. 5;

FIG. 9 is a front view of the module shown in FIG. 1, the rear view being a mirror image thereof; and,

FIG. 10 is a front view of the module shown in FIG. 5, the rear view being a mirror image thereof.
